UNITED STATES PATENT OFFICE.

SIMEON LILLEY, SR., OF DEEPWATER, MISSOURI.

FUSE-IGNITING POWDER.

1,128,158.

Specification of Letters Patent.

Patented Feb. 9, 1915.

No Drawing.

Application filed December 10, 1913. Serial No. 805,808.

To all whom it may concern:

Be it known that I, SIMEON LILLEY, Sr., a citizen of the United States, residing at Deepwater, in the county of Henry and State of Missouri, have invented a new and useful Fuse-Igniting Powder, of which the following is a specification.

The present invention relates to improvements in a fuse igniting powder, the same being composed of certain ingredients, especially adapted to be used in connection with the fuse igniting means set forth in my U. S. Patent No. 963,161, granted to me July 5, 1910, the primary object of the present invention being the provision of a powder composed of a plurality of ingredients which are comparatively safe when in the granular or powdered state, and which may be easily inserted in the central receptacle of my fuse igniting means to be detonated by the use of surfuric acid and also by a fulminating cap.

The present powder is composed of chlorate of potash, sugar, cobalt, and sulfur. In mixing the present powder, the ingredients are pulverized and are properly combined so as to be thoroughly commingled and if so desired may be mixed with water to produce a solid mass or used without water as a powder.

The preferred proportions of the present fuse igniting powder is as follows: chlorate of potash, 45%; sugar, 50%; cobalt, 3%; sulfur, 2%. The cobalt which is a metallic cobalt is pulverized and mixed in the present powder, the same assisting in reducing the flame or flash that would tend to ignite the gases in the mine. It has been found in practice that a powder containing this element or ingredient is safe and sure in its action.

What is claimed is:

1. A fuse igniting powder, composed of chlorate of potash, sugar, sulfur and cobalt.
2. A fuse igniting powder, composed of chlorate of potash, approximately 45%; sugar, approximately 50%; sulfur approximately 2%; and cobalt approximately 3%.
3. A fuse igniting powder, composed of a chlorate, sugar, sulfur and cobalt.

In testimony that I claim the foregoing as my own, I have hereto affixed my signature in the presence of two witnesses.

SIMEON LILLEY, Sr.
